Inventor:
Adam W. Kaufman
C. Horwitz

UNITED STATES PATENT OFFICE.

ADAM W. KAUFMAN, OF MILWAUKEE, WISCONSIN.

TIMER.

Application filed May 13, 1926. Serial No. 108,221.

This invention relates to timers.

In general this invention is an improvement over that disclosed in my prior Patent No. 1,582,757, of April 7, 1925, and has the same general objects of such invention.

This invention has for its further objects the provision of a novel form of timer which may be applied to the standard timer shaft as a unit, such unit including both the casing and stationary parts and the roller, and to so construct the unit that it may also be bodily removed.

Further objects are to provide a timer in which a large surface of contact is provided between the stationary brushes or contacts and the contact of the roller, so that the maximum current flow is instantly established for each of the circuits of the ignition system.

Further objects are to provide a timer which is of very simple and strong construction, and which may be readily manufactured at a small cost.

Further objects are to provide a timer in which the contacts may be very cheaply renewed if they become worn, and in which the construction is such that the contacts may be replaced with a minimum of effort.

An embodiment of the invention is shown in the accompanying drawings in which:

Figure 1 is a view of the timer with parts broken away showing the parts in their assembled position.

Figure 2 is a sectional view on the line 2—2, Figure 1.

The timer comprises an insulating casing 1 which constitutes the timer cap. It is provided with a recessed central portion 2, adapted to receive the usual attaching clip.

Further, this casing is provided with an inner annular flange 3 to fit the standard construction of the internal combustion engine. The casing carries a plurality of regularly spaced studs or bolts 4 which have inner and enlarged heads 5, and which are clamped tightly in place by means of a nut 6; such bolts projecting beyond the nuts to receive the wire terminals and thumb nuts. Between the heads 5 and the adjacent flat portions 7 of the interior of the casing, arms 8 of metal, are positioned and are clamped tightly in place by means of the heads 5, as most clearly shown in Figure 1. These arms are provided with a pair of inwardly turned

ears 9, which are received between the ears 10 of a pivotally mounted arm 11. This arm 11 is urged outwardly by means of the spring 12, such spring surrounding the split pin or pintle pin 13, which joins the ears 9 and 10. The free end of the pivotally mounted arms 11 are provided with metal contact blocks 14, and these metal contact blocks are held by means of a riveted portion 15. The contact blocks are positioned between a pair of projecting parallel ears 16, as most clearly shown in Figure 2.

The roller comprises an insulating body portion or disc 17 provided with a hub and with a metal bushing 18. This metal bushing has an outwardly extending flange 19 which joins the contact segments 20, such segments being of metal, as desired. The roller may be molded about the contacts carried thereby.

The inner bushing of the roller is provided with a key-way or recessed portion 21. This keyway is adapted to receive the elongated head 22 of a T-shaped pin. This pin is provided with an inwardly projecting portion 23, which, as may be seen from Figure 3, is adapted for positioning within the usual aperture 24 in the timer shaft 25.

It is to be noted that the roller is held against displacement from the casing by means of the overhanging inwardly projecting ears 16 of the pivoted arms 11. Thus the entire device, that is to say, the casing and the roller, is handled and positioned as a unit. It also may be removed as a unit from the shaft whenever desired.

In installing the device it is merely necessary to position the pin or key so that its head 22 parallels the axis of the shaft. Thereafter, the entire unit is slipped into place, the roller being carried by the arms 11 and being held between the ears 16. This roller freely floats upon the shaft, and thus accurately accommodates itself to the stationary contact carried by the pivoted levers 11, so that no binding or excessive friction can occur.

Further, it is impossible for the two parts of this apparatus to be misplaced, as the roller and casing are at all times held together as a unit by the inherent characteristics of the constructions of this timer.

It is also to be particularly noted that an extensive surface contact between the sta-

tionary metal contacts and the metal segment contacts of the roller is secured. Consequently the maximum current flow can occur substantially instantaneous in the ignition circuits.

It is to be noted further that this timer may be very cheaply manufactured by simple processes and, consequently, may be sold at a relatively small price.

10 Further it is to be noted that if any of the contacts should become worn, they may be readily replaced by removing the timer and loosening the corresponding bolt 4.

It is to be noted further that the rotary portion of this timer is symmetrical and, consequently, there is no unbalanced condition which would, when acted upon by centrifugal force, cause disturbances. Instead the rotary portion is merely a circular disc 20 with a metal segment, and the heavy or relatively large contact blocks are the stationary contacts.

It is to be noted particularly that the contact blocks are carried by the pivotal arms 25 in such a manner that they will accurately adjust themselves to the periphery of the roller, although the roller may be mounted on a shaft which is not exactly concentric with reference to the casing. For example, 30 when the timer is placed upon a well worn shaft this condition may easily result.

However, no harm is done, as the device is self-adjusting.

Although the invention has been described in considerable detail, such description is intended as illustrative rather than limiting as the invention may be variously embodied and as the scope of such invention is to be determined as claimed.

I claim:

A timer comprising a rotary shaft having a key therein, a roller carried by said shaft, and having a keyway therethrough and adapted to slide longitudinally of said shaft, said roller being of disc-like shape and having a segmental contact, a casing surrounding said roller, and having a plurality of terminal receiving members, stationary arms carried by each of said members, pivotally mounted arms carried by said stationary arms, springs urging said pivotally mounted arms inwardly, and a plurality of contacts carried by said pivotally mounted arms and adapted to engage the periphery of the roller, each of said contacts having front and rear ears adapted to overhang the front and rear faces of the roller.

In testimony that I claim the foregoing I have hereunto set my hand at Milwaukee, in the county of Milwaukee, and State of Wisconsin.

ADAM W. KAUFMAN.
